(57) **CLAIM**

The ornamental design for a multi IV tubing organizer, as shown and described.

DESCRIPTION

FIG. 1 is a front top right perspective view of a multi IV tubing organizer showing my new design;

FIG. 2 is a front bottom right perspective view of the present invention thereof;

FIG. 3 is a rear top left perspective view of the present invention thereof;

FIG. 4 is a rear bottom left perspective view of the present invention thereof;

FIG. 5 is a front elevational view of the present invention thereof;

FIG. 6 is a rear elevational view of the present invention thereof;

FIG. 7 is a right elevational view of the present invention thereof;

FIG. 8 is a left elevational view of the present invention thereof;

FIG. 9 is a top plan view of the present invention thereof; and,

FIG. 10 is a bottom plan view of the present invention thereof.

The broken lines shown in the figures depict portions of the multi IV tubing organizer that form no part of the claimed design.

1 Claim, 10 Drawing Sheets
